KEY ACTUATED SWITCH POST

Boley A. Andrews, Kansas City, Kans., assignor to
The Vendo Company, Kansas City, Mo., a corporation of Missouri

Application December 27, 1949, Serial No. 6,841

Term of patent 14 years

(Cl. D26—13)

To all whom it may concern:

Be it known that I, Boley A. Andrews, a citizen of the United States, residing at Kansas City, in the county of Wyandotte and State of Kansas, have invented a new, original, and ornamental Design for a Key Actuated Switch Post, of which the following is a specification, reference being had to the accompanying drawing, forming a part thereof.

Fig. 1 is a front elevational view of a key actuated switch post, showing my new design.

Fig. 2 is a side elevational view thereof; and
Fig. 3 is a top plan view thereof.

The post has been broken for convenience of illustration.

I claim:

The ornamental design for a key actuated switch post, as shown and described.

BOLEY A. ANDREWS.
